(57) **CLAIM**

The ornamental design for a storage container, as shown and described.

DESCRIPTION

FIG. 1 is a top front left perspective view of a storage container;

FIG. 2 is a top right front perspective view of the storage container shown in FIG. 1;

FIG. 3 is a bottom front left perspective of the storage container shown in FIG. 1;

FIG. 4 is a bottom front right perspective of the storage container shown in FIG. 1;

FIG. 5 is a top rear left perspective of the storage container shown in FIG. 1;

FIG. 6 is a top rear right perspective of the storage container shown in FIG. 1;

FIG. 7 is a bottom rear left perspective of the storage container shown in FIG. 1;

FIG. 8 is a bottom rear right perspective of the storage container shown in FIG. 1;

FIG. 9 is a front view of the storage container shown in FIG. 1;

FIG. 10 is a rear view of the storage container shown in FIG. 1;

FIG. 11 is a left side view of the storage container shown in FIG. 1;

FIG. 12 is a right side view of the storage container shown in FIG. 1;

FIG. 13 is a top view of the storage container shown in FIG. 1; and,

FIG. 14 is a bottom view of the storage container shown in FIG. 1.

The broken lines in the drawings illustrate the portions of the storage container that form no part of the claimed design. Shading of FIGS. 1 through 14 form no part of the claimed design.

1 Claim, 7 Drawing Sheets
